(57) **CLAIM**

The ornamental design for an electronic plastic buckle, as shown and described.

DESCRIPTION

FIG. 1 is a front perspective view of an electronic plastic buckle, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another perspective view of the electronic plastic buckle of FIG. 1 shown in an assembled state.

The broken lines in the drawings represent portions of the electronic plastic buckle and form no part of the claimed design.

(Continued)

The dot-dash lines in the drawings represent a boundary and form no part of the claimed design.

1 Claim, 9 Drawing Sheets
